(57) **CLAIM**

The ornamental design for a portion of a display screen with a changeable graphical user interface component, as shown and described.

DESCRIPTION

FIG. 1 is a front view of a portion of a display screen with a changeable graphical user interface component showing a first image in a sequence that comprises our invention; and, FIG. 2 is a front view of a second image included in the sequence.

The longer-incremented broken lines showing of a portion of a display screen of a communications terminal illustrate environment and form no part of the claimed design. The medium length broken lines illustrate the bounds of the claim and form no part thereof. The finer-incremented broken lines illustrate features of the graphical user interface that form no part of the claimed design.

The gray shading in the drawings indicates a contrast of appearance.

The subject matter in this patent includes a process or period in which an image changes into another image. The process or period in which an image transitions to another image forms no part of the claimed design.

1 Claim, 1 Drawing Sheet
